DESIGN FOR A WALL SHELF

Charles Daum, New York, N. Y.

Application February 20, 1945, Serial No. 118,065

Term of patent 7 years

(Cl. D33—3)

To all whom it may concern:

Be it known that I, Charles Daum, a citizen of the United States and a resident of the city, county, and State of New York, have invented a new, original, and ornamental Design for a Wall Shelf, of which the following is a specification, reference being had to the accompany drawing, forming part thereof, in which:

Fig. 1 is a perspective view of a wall shelf embodying my design.

Fig. 2 is an enlarged side elevational view of the shelf of Fig. 1.

My design for a wall shelf is characterized by the position of the supporting rods, rearward of the shelf centers and the enlarged fastening caps at the respective ends of the rods.

I claim:

The ornamental design for a wall shelf, as shown and described.

CHARLES DAUM.
